DESIGN FOR A FUR COLLAR

Jacob A. Silverman, Brooklyn, N. Y.

Application May 24, 1939, Serial No. 85,179

Term of patent 7 years

To all whom it may concern:

Be it known that I, Jacob A. Silverman, a citizen of the United States of America, residing in New York city, in the Borough of Brooklyn, county of Kings, and State of New York, have invented a new, original, and ornamental Design for a Fur Collar, of which the following is a specification, reference being had to the accompanying drawing, forming part thereof, wherein,

I claim:

The ornamental design for a fur collar, substantially as shown.

JACOB A. SILVERMAN.
